(57) CLAIM

The ornamental design for a garment with front pocket, as shown and described.

DESCRIPTION

FIG. 1 is a top, front perspective view of a garment with front pocket;

FIG. 2 is a bottom, back perspective view thereof;

FIG. 3 is a front, top, inside-out perspective view thereof;

FIG. 4 is a front, bottom, inside-out perspective view thereof; and,

FIG. 5 is a front inside-out view thereof.

The dashed broken lines depict portions and features of the garment with front pocket that form no part of the claimed design.

1 Claim, 5 Drawing Sheets
